CLAIM

The ornamental design for a vehicle hood, as shown and described.

DESCRIPTION

FIG. 1 depicts a front, top, left perspective view of a vehicle hood showing our new design according to a first embodiment.

FIG. 2 depicts a front, bottom, right perspective view thereof.

FIG. 3 depicts a front view thereof.

FIG. 4 depicts a back view thereof.

FIG. 5 depicts a left side view thereof.

FIG. 6 depicts a right side view thereof.

FIG. 7 depicts a top view thereof.

FIG. 8 depicts a bottom view thereof.

FIG. 9 depicts a front, top, left perspective view of a vehicle hood showing our new design according to a second embodiment.

FIG. 10 depicts a front, bottom, right perspective view thereof.

FIG. 11 depicts a front view thereof.

FIG. 12 depicts a back view thereof.

FIG. 13 depicts a left side view thereof.

FIG. 14 depicts a right side view thereof.

FIG. 15 depicts a top view thereof; and,

FIG. 16 depicts a bottom view thereof.

(Continued)

The claimed design is indicated by the relatively dark portions in the figures. The relatively light portions form no part of the claimed design. The dash lines depict boundaries of the claimed design.
